UNITED STATES PATENT OFFICE.

HAROLD E. SMITH, OF CLEVELAND HEIGHTS, OHIO.

POWER-DRIVEN WRINGER MECHANISM.

Application filed August 24, 1920. Serial No. 405,604.

To all whom it may concern:

Be it known that I, HAROLD E. SMITH, a citizen of the United States, residing at Cleveland Heights, in the county of Cuyahoga and State of Ohio, have invented a certain new and useful Improvement in Power-Driven Wringer Mechanism, of which the following is a full, clear, and exact description, reference being had to the accompanying drawings.

This invention relates to wringing machines of the type wherein a power driven wringer is supported for rotation about a vertical axis, power connections being provided whereby the wringer rolls may be driven in any position of their adjustment. The operation of such a wringer is generally effected by means of a vertical shaft co-axial with the axis of rotation as a result of which any obstruction or resistance to the operation of the rolls tends to cause the entire wringer to swing about its axis sometimes with a considerable amount of force. Even the resistance to rotation caused by the screwing down of the rolls is enough to cause the wringer to inflict a severe blow if the power be applied without first securing the wringer against movement. The objects of the present invention are the provision of means operative automatically upon the connection of the power to the wringer for securing said wringer against swinging; the provision of such a combination of operating and latching devices as to prevent the action of the former without the latter; the provision of independent means for facilitating such automatic latching action; the provision of a new, simple and inexpensive structure for performing the functions above indicated; while further objects and advantages will become apparent as the description proceeds. In the drawings accompanying and forming a part of this application, I have shown certain illustrative embodiments of my invention although it will be understood that these drawings are illustrative merely and are not intended to limit me to the particular constructions therein shown. In these drawings, Fig. 1 is a vertical, sectional view of a wringer operating mechanism embodying my improvements; Fig. 2 is a sectional view corresponding to the line 2—2 of Fig. 1; Fig. 3 is a top plan view of the support corresponding to the line 3—3 of Fig. 1; Fig. 4 is a side elevation of a modified

structure embodying my inventive idea; Fig. 5 is a sectional view corresponding to the broken line 5—5 of Fig. 4; Fig. 6 is a vertical sectional view through a modified form of bracket and operating means; Fig. 7 is a horizontal sectional view corresponding to the line 7—7 of Fig. 6; and Fig. 8 is a detail view corresponding to the line 8—8 of Fig. 7.

Describing the parts by reference characters, 1 represents a suitable support mounted upon any convenient base, such as the washing-machine casing 2, and having a flat circular upper surface 3 formed with a central socket 4 communicating with the passage 5 in which is located the driving shaft 6. Rotatably mounted on this support is the bracket 7 having attached thereto the wringer frame 8 and also having a circular head 9 resting on the support 1 and formed with a neck 10 which fits in the socket 4. Mounted on the top of the head 9 is the hollow casing 12 having at one side the hollow projection 13 extending towards the wringer frame. Journaled in vertical position in this casing is the shaft 14 which is operatively connected to the shaft 6, preferably by a separable joint 15, and journaled in the projection 13 is the horizontal shaft 16 to which is attached the driven roll 17 of the wringer. 18 represents the companion roll and 19 the tension spring. Rigidly secured to the shaft 16 inside the casing 12 is the mitre gear 20 which meshes with the similar gears 21 and 22 which are loosely sleeved on the shaft 14 and can be secured thereto in driving relation by the agency of the slidable clutch spool 23 which is splined on said shaft. This spool is moved by means of an eccentric finger 24 carried by a circular plate 25 which can be rocked by the handle 26. By rocking this handle in one direction or the other, the wringer rolls can be caused to turn in one direction or the other, and when the handle is upright the wringer rolls remain at rest.

In order to fix the position of the wringer frame I have shown the bracket 1 as formed adjacent to its upper surface 3 with a plurality of lateral notches 30—30, here four in number, and cooperating with these notches I have shown a latch 31 pivoted between cheek pieces 32—32 carried by the head 9 and having an upwardly projecting handle 33. This latch is preferably provided with a closing spring 34 by which it is

engaged. Also I provide a totally independent latching device adapted to be moved into engaging position by the same movement as that which causes the engagement of the clutch. In this embodiment such device comprises a vertically movable pin 35 having at its top an enlarged head 36 resting against a cam 37 carried by the handle 26, the parts being so arranged that when the clutch spool is in disengaged position, this locking pin will be elevated by the spring 38 so as to clear the top of the support but when the handle is rocked in either direction the pin will be depressed so as to enter suitable apertures or sockets in that support and prevent rotation of the wringer frame even though the latch 31 should be disengaged. In the present embodiment I have shown the latch 31 as entering the same socket or notch as does the latch-pin 35, this being for purposes of manufacturing convenience. The only purpose of the latch 31 is to assist in indexing the wringer frame and to hold the same in such a position that the pin 35 can be depressed without obstruction.

The embodiment shown in Figs. 4 and 5 employs the same support 1, bracket 7, head 9, casing 12, shaft 16, clutch handle 26, automatic latch 35, head 36, and cam 37. The auxiliary latch comprises two vertical reciprocable pins 40-40 located one at each side of the casing and having heads 41 midway of their length against which press the springs 42 whose upper ends rest against integral shoulders 43 formed on the casing exterior. For disengaging these latching pins I have provided a yoke 44, pivoted upon a horizontal axis 45, and having a laterally projecting handle 46 which, when depressed, raises the pins out of the sockets 47 with which the bracket is provided. The pins 40-40 are located upon opposite sides of the shaft 14, and the pin 35 half way between; the sockets 47 being likewise spaced 90° apart, it will be seen that whenever the pins 40 are in engaging position, the pin 35 is in register with the intermediate socket, thereby permitting unimpeded engagement of the wringer-clutch.

In the embodiment shown in Figs. 6 and 7, 1 represents the socket and 2 the support therefor, but the bracket here takes the form of a hollow casing 51, one end of which is pivoted about the drive shaft 50, and the other end of which carries the wringer frame 52. Loosely sleeved about the shaft 50 are two spaced sheaves 53-53, and tightly secured to the wringer shaft 54 which traverses this casing horizontally are the sheaves 55-55. Each of the first sheaves is operatively connected to one of the last sheaves by means of an extensible, flexible, driving cable 56, tightening pulleys 57-57 being preferably employed for the triple purpose of holding the cables tight and causing them

to embrace a large part of the circumference of each sheave and of causing them to run more accurately toward and away from said sheaves.

Slidably mounted on the shaft 50 is the clutch spool 58 adapted to engage either of the sheaves 53. On opposite sides of the shaft 50 are located the vertically movable locking pins 60 whose upper ends are articulated to the rocker 61 which is pivoted upon a horizontal finger 62 located between the sheaves 53. A clutch lever 64 has one end pivoted at 65 and the other end equipped with a yoke 66 engaging the clutch spool, its intermediate portion being connected by the link 67 to the handle 68 whereby the clutch is moved in one direction or the other according to the way said handle is thrown. This clutch lever is also suitably attached at the point 70 to the rocker 61, so that when the clutch is in mid-position, the rocker is horizontal and neither pin projects beneath the surface of the casing; but when the clutch is moved in either direction, one or the other of said pins is depressed into engagement with the corresponding socket 71. In order to facilitate such a setting of the casing as will bring these pins into alignment with their sockets I have shown one wall of the casing as provided with an integral boss 72 having mounted therein the round-nosed, spring-pressed plunger 73 adapted to snap into a suitable depression in the adjacent face of the supporting bracket at such times as the pins 60 register with their sockets. In the present embodiment I have illustrated this plunger as located at 90° from the pins 60 and arranged to snap into one of the same sockets 71, but this is a mere detail adopted for manufacturing convenience.

It will be understood that while I have shown only four sockets or wringing stations the same might be increased to any number, or decreased if desired; also that the arrangement, design, and mounting of the latching devices can be changed; also that while I have described the illustrative embodiments with considerable particularity, I do not restrict myself to those particular constructions nor in any other way except as particularly recited in the attached claims.

Having thus described my invention, what I claim is:

1. In a device of the character described, the combination with a wringer pivoted about a vertical axis and a driving member concentric with said axis for operating the same, of means for making and breaking the operative connection between said member and wringer, means operable by said first means for latching said wringer in fixed position relatively to said vertical axis during the time that such operative connec-

tion exists, and a spring pressed latch independent of said first means for holding said wringer in position to be latched by the second named means.

5. 2. In a device of the character described, the combination of a support, a vertical shaft journaled therein, a wringer pivoted for movement about a vertical axis concentric with said shaft, means including a 10 clutch for connecting the wringer mechanism to said shaft, a spring pressed latch adapted to hold said wringer against swinging, and a latch operatively connected to said clutch for holding said wringer independently of said first latch during the time 15 that said clutch is engaged.

3. In a device of the character described, the combination with a support and a bracket pivoted thereto, rotating devices 20 carried by said bracket, a drive shaft, power transmitting means carried by said bracket for connecting said rotating devices to said drive shaft, said means including a clutch, and a pair of independent latching devices 25 adapted and arranged to secure said bracket against pivotal movement, there being sockets for said latch members, one of said latch members operatively connected to said clutch so as to permit the engagement of 30 said clutch only upon the insertion of such latch member into a socket, and the other latch member being arranged to register with a socket simultaneously therewith.

4. In a device of the character described, 35 in combination, two members pivoted together, a drive shaft concentric with the

pivot axis, wringer mechanism carried by one of said members, disconnectible driving means between said shaft and wringer mechanism, and two independent latch devices adapted to prevent relative rotation of said members, one of said latch devices operatively associated with the driving mechanism so as to be operative during the time that said shaft is connected to said 40 mechanism, and the other adapted to hold said members in position to facilitate the engagement of said first latch device.

5. In a device of the character described, in combination, two members pivoted together, a drive shaft concentric with the pivot axis, wringer mechanism carried by one of said members, disconnectible driving means between said shaft and wringer mechanism, and a pair of independent latch- 50 ing means for said members, each means comprising a movable device carried by one member adapted to engage any one of a plurality of sockets formed in the other member, both of said latch devices registering each with a socket at the same instant, one of the same being spring-pressed away from its socket and the other being spring-pressed toward its socket, means for inserting the former latch device into its socket 55 by the same movement which connects said shaft to said wringer mechanism, and independent means for withdrawing the latter latch device out of its socket.

In testimony whereof, I hereunto affix my 70 signature.

HAROLD E. SMITH.
